Patented Mar. 29, 1921.

UNITED STATES PATENT OFFICE.

BENJAMIN B. LACY, OF HOUSTON, TEXAS.

CABLE-CLAMP.

1,372,704.

Specification of Letters Patent. Patented Mar. 29, 1921.

Application filed December 3, 1919. Serial No. 342,227.

To all whom it may concern:

Be it known that I, BENJAMIN B. LACY, a citizen of the United States, and a resident of Houston, in the county of Harris, 5 State of Texas, have invented certain new and useful Improvements in Cable-Clamps, of which the following is a specification.

As heretofore practised, particularly in drilling oil and water wells, and where a 10 cable is used, a suitable clamp is employed on the rig to hold the cable. When necessary to employ different sized cables, the gripping members of the clamp must be changed accordingly. This change of gripping 15 members, regardless of the time required to make the same, is quite a disadvantage, in that it usually necessitates having the changeable members accessible, which is not always convenient.

20 The object of the present invention is to so construct the clamp, particularly the gripping members, that it may accommodate cables of different sizes by manipulating the members to change their relative cable-receiving positions.

The preferred embodiment of the invention is illustrated in the accompanying drawing, in which—

Figure 1 is a plan view of a clamp, illustrating the application of the invention;

Fig. 2 is a side elevation; and

Fig. 3 is a detail perspective view of one of the gripping members.

Referring now to the drawing by numerals of reference, 5 represents a pair of opposed operating jaws, pivoted together as at 6, and having their opposite ends reduced as at 7, one of the ends being provided with a swinging clamping yoke 8, pivoted as at 40 9, with its opposite end adapted to be swung over the end of the other jaw, and produce a clamping effect of the jaws by means of the pressure screw 10, having a threaded engagement with the yoke 8, as at 11, and 45 with its end 12 bearing against the side of the jaw. Carried by each of the operating jaws 5 are the gripping members 13, comprising relatively long cylinders having a plurality of cable-receiving and gripping 50 recesses in their sides, whereby, when two opposed recesses are presented in confronting relation, they may grip the cable 15 and positively hold the same against movement. In order to accommodate the clamp to dif-

ferent sized cables, the recesses 14 in the 55 sides of the gripping members 13 are of different sizes; thus, cables of different diameters may be clamped by rotating the members 13 to bring the desired sized recesses in gripping relation with the cable. 60 The members 13 are maintained against rotation by means of set screws 16, carried by the lugs 17 on the jaws 5, and with their ends protruding through the lugs and seated in the relatively small recesses 18 in the 65 web portion of the members 13. Ordinarily, the gripping members 13 may be freely rotated; however, should they stick, means are provided to insure their rotation, which comprises upwardly extending lugs 19 having openings 20 made to receive a pin. Thus, it will be seen that by releasing the set screws 16 the members may be rotated to bring the proper cable-receiving recesses into gripping position. As is common in 70 clamps of this kind, suitable rings 21 are employed for suspending the clamp.

Not only is the employment of the gripping members quite an improvement over the effect produced by the conventional type, 80 but they greatly increase the efficiency of the clamp, in that they are always carried by the clamp, thus overcoming the disadvantage of replacing different sized ones when cables of different size are employed. 85

Claims.

1. A cable clamp, comprising a pair of opposed operating jaws, gripping members rotatably carried by said jaws and having a plurality of cable gripping recesses, said 90 gripping members being adapted to be rotated to bring two opposed recesses in gripping relation to the cable.

2. A cable clamp, comprising a pair of opposed operating jaws, gripping members 95 rotatably carried by said jaws and having a plurality of cable gripping recesses, said recesses being of different dimensions to enable the same to grip different sized cables, said gripping members being adapted 100 to be rotated to bring two opposed recesses in gripping relation to the cable.

3. A cable clamp, comprising a pair of opposed operating jaws, gripping members carried by said jaws and having a plurality 105 of cable gripping recesses rotatable to bring two opposed recesses in gripping relation to the cable, the recesses in said gripping

member being of different dimensions to adapt the grip to different sized cables, said gripping members being provided with means for holding two opposed recesses in cable gripping position, and means for rotating the members when released by the holding means.

4. A cable clamp such as set forth in claim 3, in which the said holding means comprises a set screw carried by each of the operating jaws, having a seat on the gripping members between the recesses.

BENJAMIN B. LACY.
